UNITED STATES PATENT OFFICE.

GUSTAV A. CARLSON, OF CHICAGO, ILLINOIS, ASSIGNOR TO THE BOYE NEEDLE COMPANY, OF CHICAGO, ILLINOIS, A CORPORATION OF ILLINOIS.

CAN-OPENER.

1,336,126.

Specification of Letters Patent.

Patented Apr. 6, 1920.

Application filed June 26, 1919. Serial No. 306,817.

To all whom it may concern:

Be it known that I, GUSTAV A. CARLSON, a subject of the King of Sweden, residing at Chicago, in the county of Cook and State of Illinois, have invented a new and useful Improvement in Can-Openers, of which the following is a specification.

This invention relates particularly to can-openers of the type adapted to the purpose of opening sealed tin cans, and the primary object is to provide a device of this character which can be manufactured at very small cost, and which is well adapted to its purpose.

The invention is illustrated in its preferred embodiment in the accompanying drawing, in which—

Figure 1 is a perspective view of a can-opener embodying the invention; Fig. 2, a broken side elevational view of the same; Fig. 3, a broken plan view of the same, the dotted lines indicating brokenly a can; Fig. 4, a transverse sectional view of the fulcrum-member of the device, the section being taken as indicated at line 4 of Fig. 3; and Figs. 5, 6, and 7 views similar to Fig. 4, showing different forms of anti-slip edges with which the fulcrum-member may be provided for the purpose of preventing slipping during the cutting operation, which is performed by a prying operation.

The improved device comprises a blade 1 having a shank 1^a which forms an obtuse angle with the blade; and a handle 2 on which the blade is rigidly mounted through the medium of its shank.

The blade and shank may be formed from a suitable bar of steel whose end-portion is furcated. One of the furcations is fashioned to provide the blade 1 which is curved both edgewise, or in its own plane, and in a transverse plane, to conform, in a general way, to the contour of the circumference of the can. The other furcation, which lies beneath or back of the blade 1 is shortened and bent so as to extend crosswise beneath the lower edge of the base-portion of the blade 1, thus affording a transverse fulcrum-member 1^b, adapted to bear upon the upper edge-portion of the can. The furcations are provided by splitting the end-portion of the steel bar initially; and the bearing, or fulcrum-member 1^b, is provided by shortening the lower furcation, bending the metal somewhat out of the plane of the blade, and then

bending it crosswise of the blade, so that the fulcrum-member projects beyond both sides of the shank, as will be most clearly understood from Fig. 3.

The blade 1 is provided with a bevel 3 which produces a sharp cutting edge 3^a, which is flush with the outer surface of the blade, that is, with the convex side of the blade. The blade also curves downwardly away from the plane of the upper edge of the shank 1^a, so that the blade forms, in effect, an obtuse angle with said shank. At the extremity of the blade is provided a penetrating point 4 which is adapted to pierce the metal of the top of the can. The point 4 extends at about the same angle with reference to the handle 2 as does the shank 1, so far as downward inclination is concerned, and said point has a blunt upper surface 4^a, which may be slightly rounded. The purpose of this blunt surface is to provide a bearing which will engage the lower surface of the top wall of the can at the end of a cutting stroke, so that the tin will not be torn and the blade will always have its point beneath the top of the can, after it has once been entered. Preferably the penetrating point 4 is offset inwardly slightly from the plane of the blade, so that while the point may move in contact with the circumferential wall of the can, the cutting edge of the blade will operate to shear the metal off the top close to the corner of the can.

The fulcrum-member 1^b lies substantially below and back of the blade 1, and it will be noted from Fig. 2 that the blade is so curved downwardly as to bring the point-portion 4 substantially in front of the fulcrum-member. The lower edge of the fulcrum-member is preferably beveled rearwardly and upwardly, so as to provide an anti-slip corner 5, as shown in Fig. 4.

Figs. 5, 6, and 7 show the same fulcrum-member with the anti-slip edge formed according to slight variations. Thus Fig. 5 shows the edge 5^a formed by a double bevel; Fig. 6 shows the edge 5^b formed by a single bevel which inclines rearwardly and downwardly; and Fig. 7 shows an edge 5^c formed by hollow-grinding the lower edge of the fulcrum-member. The exact detail is unimportant, but it is desirable to provide in some suitable manner against slippage.

The operation will be readily understood.

Fig. 3 shows a plan view of the can-opener 110

in relation to the outline of the upper portion of the can. In opening a can, the handle is elevated until the point 4 is substantially vertical; the blade is then forced through the metal of the top of the can until the fulcrum-member 1^b bears upon the edge-portion of the can; the operator then depresses the handle, causing the cutter edge 3^a to sever the tin until the blunt surface 4^a of the point of the blade engages the lower surface of the can-top. A fresh hold is then taken by elevating the handle and moving the device ahead until the base-portion of the blade engages the tin and the fulcrum-member engages the can in the new position. Downward pressure of the handle then causes a fresh cut to be made. The operation is repeated as often as may be necessary.

It will be understood that the device constitutes, in effect, a lever of the first class, the blade, or the shank-portion of the blade, being equipped with a fulcrum-member which is adapted to bear on the corner of the can, this member being preferably rigid and formed integrally with the shank-portion of the blade. Again, the angle which the cutting portion of the blade forms with the shank of the blade and the angle which the handle forms with relation to the shank of the blade render the device very convenient in use. It will be noted in Fig. 3 that while the cutting portion of the blade conforms, in a general way, to the circumference of the can, the angles of the device are such as to throw the grip-portion of the handle well

away from the can at the end of the cutting stroke, so that there is no possibility of injuring the hand, even in case such pressure should be exerted in the cutting operation as to cause the point-portion of the blade by 40 any chance to tear the metal and allow the hand to descend unexpectedly under the force being applied.

As shown, the shank-portion of the blade is preferably provided with a perforation 45 6, by means of which the device may be hung upon a nail or hook.

The foregoing detailed description has been given for clearness of understanding, and no unnecessary limitations should be 50 understood therefrom, but the appended claim should be construed as broadly as permissible, in view of the prior art.

What I regard as new and desire to secure by Letters Patent is:

A can-opener in the form of a lever of the first class, comprising a handle and a blade having a transversely curved portion provided with a forwardly and upwardly presented cutting edge and provided with a 60 penetrating point having a blunt upper wall, said blade having at its lower edge-portion a furcation which is bent laterally from the plane of the blade and then bent back and extended across the lower edge of the blade 65 back of the cutting portion to afford a transverse fulcrum member adapted to bear on the can.

GUSTAV A. CARLSON.
